CLAIM

The ornamental design for joy stick with rotational element, as shown and described.

DESCRIPTION

FIG. 1 is a side perspective view of the joy stick with rotational element the according to the invention, showing our new ornamental design;

FIG. 2 is a top plan view thereof; and

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view having the joy stick with the rotational element in an alternative position;

FIG. 9 is a top plan view having the joy stick with the rotational element in another position;

FIG. 10 is a top plan view having the joy stick with the rotational element in still another position; and,

FIG. 11 is a top plan view having the joy stick with the rotational element in a fully rotated position.

The broken lines are for illustrative purpose only and form no part of the claimed design. The drawing FIGS. 8-11 are drawn in reduced scale.
